CHECKERBOARD

Henry Allen Wilson, 1000 Eldorado Ave.,
Clearwater Beach, Fla.

Filed June 24, 1963, Ser. No. 75,502

Term of patent 14 years

(Cl. D34—5)

Fig. 1

Fig. 2

FIG. 1 is a plan or face view of a checkerboard embodying my new design.

FIG. 2 is a fragmentary view of another embodiment of my game board design wherein the outermost corners are equally divided in quadrants of the four colors used in FIG. 1.

The game board design is of conventional thickness.

The essential feature of my design resides in the combination on the game board disclosed of vertical and horizontal grid lines forming a pattern of 64 squares each of which, except for the four corner squares, is alternately bisected on the angle into two differently colored triangles, so that diagonal rows of like squares extend diagonally across the board, all as shown.

I claim:

The ornamental design for a checkerboard, as shown and described.
